 a corporation of Connecticut

Application July 28, 1932, Serial No. 625,441

3 Claims. (Cl. 15—104.01)

This invention relates to improvements in tools for working on guides for the valve stems of internal combustion engines.

The principal objects of the invention are 5 directed to the provision of a tool for cleaning guides for the stems or valves of internal combustion engines and the tool of the invention is so constructed and arranged that it may be inserted in a valve stem guide and rotated or 10 oscillated therein for cleaning the guide and freeing it of carbon deposits and other foreign substances.

According to a special feature of the invention the tool is so arranged that it may be expanded 15 while in the guide to obtain the most effective cleaning action and is constructed in a simple manner so as to be economical to manufacture and yet it has such novel characteristics as renders it efficient in its operation.

20 Various novel features and advantages of the invention will be hereinafter more fully referred to in connection with the accompanying drawings wherein:

Fig. 1 is a side elevational view of a tool embodying the novel features of the invention.

Fig. 2 is a sectional view on the line 2—2 of Fig. 1.

Fig. 3 is a perspective view of one of the cleaning elements of the tool.

30 Fig. 4 is a sectional view on the line 4—4 of Fig. 1, and

Fig. 5 is a diagrammatic view showing a developed plan view of the working edges of the elements of the tool.

35 Referring now to the drawing more in detail the invention will be fully described.

A cleaning head assembly is provided which is represented generally by 2 and includes an upper flange 4 and a lower flange 6 between 40 which extend a plurality of circumferentially arranged cleaning elements 8.

The cleaning elements 8 are preferably made from metal strips which have one or more flat faces or sides. In the form of the invention 45 shown the elements 8 are in the form of flat and relatively thin metal strips which are twisted intermediate their ends to provide intermediate portions tangential to the axis of the tool and more or less parallel with, and in the 50 same plane as, the end portions thereof and to present a plurality of working edges such as 10. The strip will be of metal which is more or less springlike so as to be resilient or yieldable. The opposite ends of the strips are secured in 55 some suitable manner to the members 4 and 6

as by being brazed or welded in suitable sockets 15 thereof, whereby the cleaning elements and the flanges form a cleaning head assembly.

Preferably the members 8 will be twisted so that the working edges 10 will extend longitudinally of the head assembly and in an angular relation relative to the axis of the tool whereby in rotating the tool in a valve guide the said working edges will operate with a shearing action.

The lower flange 6 has a threaded part 14 in screw threaded engagement with the shank 16. The upper end 19 of stem 18 may be threaded in flange 4 and a nut 20 is in threaded engagement with the threaded end 19 of said stem and serves 70 as a lock nut, it being adapted to bear on the flange 4. The stem 18 has a lower threaded end 75 slidably in a suitable hole of a handle H and is in threaded engagement with a nut 24 rotatable in a slot 26 of said handle.

By rotating the nut 24 in one direction, the stem 18 may be moved downwardly whereby the nut 20 thereof tends to move the upper flange toward the lower flange and press on the elements 8 so as to bulge or expand the overall 80 diameter of the cleaning head. When the nut 24 is rotated in an opposite direction the member 18 is moved upwardly and the upper end, being locked to the flange 4, will move the flanges apart and relieve the members 8 of end- 85 wise pressure. The stem 18 is held against rotation when member 24 is rotated since its upper end is locked to part 4 as described and the elements 8 have their opposite ends fixed to the flange members 4 and 6 to act as torque members while the member 6 is threaded in shank 16.

While the shank 16 in the form of the invention shown is provided with a handle 4, it will be readily apparent that the shank may be embraced in a chuck or other driving mechanism. In any event it will be desirable to provide means in association with the stem so as to facilitate expanding or increasing the diameter of the tool to facilitate movements of the flanges 4 and 6 towards and away from one another for expanding or adjusting the overall diameter of the elements 8.

In operation, the cleaning head assembly 2 is inserted within a valve guide and the shank 16 is rotated by means of the handle 8 or otherwise. The rotation of the tool causes the working edges 10 to act on material on the walls of the guide so as to scrape and remove the same therefrom. When desired or necessary the tool 110

may be expanded while in the bore by moving the flanges 4 and 6 towards one another.

As pointed out the elements 8 are twisted intermediate their ends to provide intermediate portions which are tangential to the axis of the tool and more or less in parallelism with and in the same plane as the opposite ends of the elements. This provides working edges 10 which extend between the intermediate and end portions in an angular relation relative to the axis of the tool. The adjacent working edges of adjacent elements are arranged in alternately converging and diverging relation, as shown, to overcome longitudinal or axial self-feeding of the tool as it is rotated in a valve guide bore. When the tool is rotated in a valve guide bore the angularly disposed working edges represented by 10 in Fig. 5, act with a shearing action which may tend to produce impulses or forces effective in the direction of arrows f to feed the tool in one direction. The working edges represented by 10' may produce opposing impulses or forces in the direction of arrows f' to feed the tool in an opposite direction. Thus any tendency of the tool to feed in one direction is offset by an equal tendency to feed in an opposite direction, and is accomplished by arranging the working edges in the relation described. A self-feeding or screw action of the tool would not only tend to mar the valve guide bore but the desired shearing action would be impaired thereby.

Various changes may be made in the form of the invention shown without departing from the spirit and scope thereof and therefore it is desired to be limited by the following claims rather than by the foregoing description.

What is claimed is:

1. A tool for cleaning the bores of valve guides comprising in combination, a staff, flanges relatively movable axially thereon, and a plurality of cleaning elements ribbon-like in form each having opposite end portions secured to said flanges in substantial parallelism and in the same plane, the said elements being twisted intermediate their ends to form intermediate portions substantially parallel with the end por-

tions thereof and provide working edges extending from the intermediate portions to the end portions in an angular relation relative to the axis of the tool, the adjacent working edges of the elements being arranged in alternate diverging and converging relation, whereby the tendency of the tool to self-feed along the bore in one direction is overcome by a tendency to self-feed in an opposite direction.

80

2. A tool for cleaning the bores of valve guides comprising in combination, a staff, flanges relatively movable axially thereon, a plurality of cleaning elements ribbon-like in form each having opposite end portions secured to said flanges in substantial parallelism and in the same plane, the said elements being twisted intermediate their ends to form intermediate portions in the same plane and substantially parallel with the end portions thereof and provide working edges extending from the intermediate portions to the end portions in an angular relation relative to the axis of the tool arranged in sets of working edges above and below the said intermediate portions, the adjacent working edges of the elements in each set being arranged in alternate diverging and converging relation, whereby the tendency of the tool to self-feed along the bore in one direction is overcome by a tendency to self-feed in an opposite direction, and means to effect relative movements of said flanges.

85

3. A tool for cleaning the bores of valve guides comprising in combination, a staff, flanges relatively movable axially thereon, and a plurality of cleaning elements ribbon-like in form, each having opposite end portions secured to said flanges in substantial parallelism and in the same plane, the said elements being twisted intermediate their ends to provide working edges disposed in an angular relation relative to the axis of the tool, the adjacent working edges of the elements being arranged in alternate diverging and converging relation, whereby the tendency of the tool to self-feed along the bore in one direction when rotated therein is overcome by its tendency to self-feed in an opposite direction.
